 a corporation of Delaware

Application December 10, 1936, Serial No. 115,171

6 Claims. (Cl. 200—90)

This invention relates to electromagnetic vibratory devices such as are used in voltage supply circuits and the like.

An object of the invention is to improve such vibratory devices.

Other objects of the invention will be apparent from the following description and accompanying drawings taken in connection with the appended claims.

The invention comprises the features of construction, combination of elements, arrangement of parts, and methods of manufacture and operation referred to above or which will be brought out and exemplified in the disclosure hereinafter set forth, including the illustrations in the drawings.

In the drawings:

Figure 1 is a side elevation of a vibrator and the grounding cup therefor;

Figure 2 is a bottom view of the assembly of Figure 1;

Figure 3 is a section on the line 3—3 of Figure 1;

Figure 4 is a longitudinal section of the vibrator;

Figures 5 and 6 are perspective views of the sound and vibration insulating members of the vibrator;

Figure 7 is another longitudinal section of the vibrator;

Figure 8 is a section on the line 8—8 of Figure 7;

Figure 9 is a section on the line 9—9 of Figure 7;

Figure 10 is an exploded view of parts of the vibratory reed and contact assembly of the vibrator; and

Figure 11 is a diagrammatic view of one circuit in which said vibrator may be used.

While a preferred embodiment of the invention is described herein, it is contemplated that considerable variation may be made in the method of procedure and the construction of parts without departing from the spirit of the invention.

In the following description and in the claims, parts will be identified by specific names for convenience, but they are intended to be as generic in their application to similar parts as the art will permit.

Referring to the drawings the vibrator comprises a metal can 11 enclosing the operating parts of the unit, the can 11 preferably being extruded or drawn from a single piece of metal, such as zinc or cadmium, although other metals, for example, iron can also be used. The end 12 of

can 11 is tapered in thickness, the thinnest portion being at the center and the thickest portion at the edges. This materially reduces the diaphragmatic radiation from the end of the can when the vibrator is in operation.

At the other end 13 of can 11 is a disc 14 of sheet insulating material, such as sheet Bakelite, in which are mounted the connecting prongs 15 of the vibrator. Disc 14 is provided with an ear or lug 19 which extends through a co-operating opening near the end of can 11, the end 13 being turned over the edge of the disc at a point opposite lug 19 to secure the disc in place. If desired the end 13 of the can may be spun or crimped over disc 14 around the entire periphery.

A grounding cup 16 fits over the end 13 of can 11 with its prongs 17 pressing against the sides of the can in electrical contact therewith. In mounting the vibrator for operation it is preferred that the grounding cup 16 be secured against and in contact with a flat metal panel or chassis by rivets or screws passing through holes 18 in the ground cup and with the connecting socket for the vibrator located in the central opening of the cup. The vibrator can then be inserted into the grounding cup 16 with prongs 15 in the connecting socket, the grounding cup serving as a mechanical support for the vibrator and also providing a low-impedance path to ground for any high-frequency static or "hash" developed by the opening and closing of the vibrator contacts.

The vibrator unit within can 11 is enclosed within sponge rubber sheaths 20 and 21 for purposes of sound and vibration suppression. Sheath 20 is a generally rectangular hollow cup of molded sponge rubber having a projecting boss 22 extending out from the middle of its closed end and a pair of beveled ridges 23 extending along two opposite sides, respectively, adjacent the open end of the sheath. When sheath 20 is inserted in the can 11 the boss 22 rests against the center of end 12 of the can and ridges 23 against the inside cylindrical wall of the can.

Sheath 21 comprises a double-ended cup of molded sponge rubber exteriorly of generally cylindrical shape and having recesses 25 (Figure 6) and 26 (Figure 7) in the respective ends thereof. The opposite sides of sheath 21 are beveled, as at 24, to increase the spacing from the wall of can 11.

When the vibrator is assembled the vibrator unit, comprising the electromagnet 28, vibratory reed 29 controlled thereby, the contacts cooperating with the reed and the frame supporting

these parts and securing them together in co-operating relation, is held within the closed chamber formed by recess 25 in sheath 21 and recess 27 in sheath 20, the ends of sheaths 20 and 21 being held together by the end walls of the can.

This arrangement affords a kind of cantilever suspension for the sheaths and the vibrator unit inside it thereby allowing considerable freedom 10 of vibration of the end portion 24 of the assembly within the can 11 without transmitting the vibrations to the can to any great extent.

Suitable perforations are made in dividing wall 30 in sheath 21 to accommodate the conductors 15 64 which connect the vibrator unit to the prongs 15.

The electromagnetic vibrator unit within the sponge rubber sheaths comprises frame 32 formed of a flat bar of metal of high magnetic permeability, such as iron, bent into what might be termed 20 a rectangular hook shape so as to provide an elongated shank portion 33, a short transverse portion 34 at one end of the shank portion, and a short reverse portion 35 at the outer end of the 25 transverse portion, the reverse portion 35 being parallel or substantially parallel to the shank portion 33. The shank portion 33 and transverse portion 34 are preferably, although not necessarily of equal width and thickness but the reverse portion 35 is preferably considerably narrower than the other portions so that the coil 28 may be conveniently fitted over it. The single 30 piece frame and core member adapts itself to precision manufacture, so that very little individual adjustment of the units is required.

Coil 28 is a winding of insulated wire on a bobbin 36 comprising a single molded piece of insulating material such as "Bakelite". The central opening in form 36 is just sufficient in size 40 to fit over reverse portion 35 of the frame with a snug fit so that the reverse portion comprises the core of the coil. If necessary the end or pole 37 of reverse portion 35 may be enlarged slightly after the coil form is in place by hammering 45 or pressure to lock the coil form in place. With the coil mounted on the reverse portion in the manner described the magnetic variations caused by current variations in the coil are concentrated and made most effective at the pole 50 of the core where they may be effective in controlling the reed.

The free end of shank portion 33 of the frame 32 is reduced slightly in thickness to provide an 55 accurately planed flat surface 38 against which rests one end of a stack 39 of operating parts and spacers including an end of reed 29 and its co-operating contacts. The stack is held to the frame by the pair of stack screws 40 passing through the shank portion 33 of the frame and held by nuts 41.

The stack 39 (starting at face 38 of the frame) comprises a thick metal spacer 42 threaded to receive the two stack screws 40, an insulating 60 sheet spacer 43 of fibre, ceramic, mica, mica substitute, synthetic resin, anodized aluminum or other suitable material, a pair of contact springs 44 and 45 mounted side by side over respective insulating bushings 61, a pair of stop arms 46 and 70 47 individual to the contact springs 44 and 45 respectively and similarly mounted, an insulating sheet spacer 48, a metal plate 49, end of reed 29, metal plate 50, contact shim 59, insulating sheet spacer 51, stop arms 52 and 53, contact 75 springs 54 and 55 individual to arms 52 and 53.

insulating spacer 56, contact shim 60, metal plate 57 and spring plate 58.

A pair of insulating sleeves 61 cover screws 40 between plates 42 and 57 so that the screws are insulated from the contact springs. Contact shims 59 and 60 are joined by a metal strip 62 thereby providing an electrical connection between the reed 29 and the frame 32. Stop arms 46, 47, 52 and 53 and plate 50 are each provided with soldering lugs such as 63 (Figure 10) at 10 the sides of the stack and insulated wires 64 are soldered at one end to these lugs and at the other end to prongs 15 of the unit. A shim may also connect adjacent stop arms, such as 52 and 53, together (and thereby their associated contact 15 spring). A wire 65 may connect one of the stop arms (and its associated spring) with one end of the winding of coil 28, the other end of the winding being grounded to frame 32 (thus being connected to the reed through jumper 62). 20 Spring plate 58 may be of spring steel having a concave-convex bias about a longitudinal axis so that when screws 40 are tightened into position a constant compression will be applied to the stack 39 and any tendency to loosen after extended use will be overcome. Lock washers also may be provided beneath nuts 41, if desired.

It will be understood that variations can be made in the stack assembly. For example, shims may be inserted at various places to adjust the 30 spacing. Likewise, in some instances, the end of shank 33 of the frame may be extended by a transverse lug to make contact with the base of reed 29 to improve the magnetic path between the frame and reed. This can also be accomplished by providing a transverse lug on metal plate 42 provided it is of magnetic permeable material, or by bending an extended portion of the reed down against the frame.

Reed 29 comprises a strip of thin spring metal, 40 preferably of magnetically permeable material such as steel, and has a pole piece 66 of magnetic permeable material, such as iron, riveted or welded to its free end. The free end of the reed is offset with respect to pole 37 of the electromagnet (formed by coil 28 plus the frame 32) 45 so that a magnetization of the electromagnet will attract the reed pole piece and draw the reed in the direction of contact springs 54 and 55. Pole piece 66 is comparatively heavy with respect 50 to the stiffness and mass of the reed assembly so that it largely dominates the reed vibration.

A pair of metal stampings 67 and 68 are riveted to opposite faces of reed 29 by rivets 69 which pass through both stampings and the 55 portion of the reed located between the clamped and free end thereof, relatively nearer the clamped end. Stampings 67 and 68 each carry a pair of integral tongues 70, 71 and 72, 73 respectively which are spaced from the reed and 60 whose ends are substantially parallel to the reed and extend toward the free end thereof. A contact disc 74 is secured to the outer face of each tongue at the end thereof. Contacts 74 are preferably of tungsten or the like. While they may 65 be of considerable thickness, as shown, it may in some instances be desirable to make them very thin, for example, of a thickness in the order of 0.02 inch. An advantage in using the thin tungsten discs on the contact springs resides in 70 their light weight which introduces less inertia deflection in the portions of the springs beyond the stop arms. The springs thus have less tendency to bounce away from the stop arms during operation.

Reed 29 is provided with a transverse slot or opening 75 between its clamped end and the portion where the stampings 67 and 68 are secured. This slot greatly increases the flexibility 5 of this part of the reed, thus greatly improving the starting characteristics of the vibrator since less magnetic pull is required to close the contacts than would be necessary without the slot.

A second opening 76 is provided in reed 29 between the place where the stampings are secured and the free end of the reed. Opening 76 is tapered in width; being widest near the free end and tapered to a rounded point near the central portion of the reed. This controls the stiffness 15 of the reed so that its stiffness near the stampings is greater than near the pole piece. As a result of this the curvature of the reed during vibration will be approximately constant over a considerable length instead of being greater at 20 one point than at another. This produces approximately uniform fibre stress throughout most of the flexing portion of the reed so that breakage is reduced. Hole 76 also reduces the sound radiation of the reed which would otherwise result 25 due to diaphragm action and reduces the air load on the reed. This reduction in air load enables the reed to vibrate at higher speeds with greater stability and less damping during operation. Likewise greater contact pressures will 30 result and the amplitude of the reed vibration will be increased.

Contact springs 44, 45, 52 and 53 each carry a contact disc 77 near their ends and positioned so as to co-operate with contacts 74 on the reed 35 tongues.

In some instances as where contact springs 45 and 55 are connected in the primary circuit of a potential changer system and springs 44 and 54 are in the secondary, or high potential circuit, the spring 45 and 55 may be thinner than springs 40 44 and 54 the extra space being made up in the stack by shims individual to the thinner springs. This provides greater contact pressure on the springs 44 and 54 so that the contact is improved 45 in the high potential circuit. Other means could also be used to provide different stiffness in certain of the springs.

The springs 44, 45, 52 and 53 are each bent at a slight angle along a line 78 at a point that lies beyond the edge of the stack not more than one-third the exposed length of the stop arms. The bends 78 are shown somewhat exaggerated in Figure 10. When the springs are clamped in the stack their outer regions lie flat against the stop, as shown, for example, in Figure 8. The spring has substantially no tendency to bounce during operation. In order to provide greater contact pressure on the rectifier (or high potential) contacts the bend can be made somewhat greater for these contact springs so that their initial pressure against the stop arms is greater. This expedient can be used either with or without the thicker springs described above.

In operation the vibrator unit can be used in 65 any of the customary potential changer circuits of the prior art such as that shown in Figure 3 of Patent #2,049,310. In this circuit each of contact springs 44, 45, 54 and 55 is in a separate branch of the circuit.

According to another arrangement the contact 70 springs 44 and 45 are connected together (as by a bridging shim in the stack) and contact springs 54 and 55 are similarly connected together so that each pair is, in effect, a single contact except for the obvious advantage of lower resist-

ance and less chance of erratic contact where dual contacts are used. This parallel contact arrangement provides an interrupter such as could be used for primary circuit interruptions only, where the secondary current is rectified by 5 some form of rectifying device. Figure 11 is a circuit diagram showing parts of such a circuit.

According to a modification of the structure herein described only one contact spring may be provided on each side of the reed and a single 10 contact will then be attached to each side of the reed to co-operate therewith. The contacts, in this instance, will be centered with respect to the reed. This provides a structure adapted for use in a primary interrupter circuit of the type just 15 described.

The vibrator structure disclosed provides a very fast contact break during operation due to the provision of stop arms 46, 47, 52 and 53 and the mounting of contacts 74 on tongues 70, 71, 72 20 and 73. This materially reduces the arcing at the contacts during break.

Vibrators according to the present invention can be made of very small size, for example, in the order of 1½ inches in diameter and 3 inches 25 long.

While the present invention, as to its objects and advantages, has been described herein as carried out in specific embodiments thereof, it is not desired to be limited thereby but it is intended to cover the invention broadly within the spirit and scope of the appended claims.

What is claimed is:

1. An electromagnetic vibratory interrupter comprising a frame, an electromagnet coil 35 mounted on one end thereof and a vibratory reed mounted on the opposite end thereof and having its free end extending toward the first mentioned end of said frame, electrical contacts controlled by the vibration of said reed, said frame 40 consisting of a continuous piece of magnetically permeable material having an elongate shank comprising the main body of the frame, a transverse portion integral with one end of said shank and transverse thereto and a reverse portion integral with the outer end of said transverse portion and substantially parallel to said shank with its free end extending toward the opposite end thereof, said coil being mounted on said reverse portion so that the free end of said portion comprises a pole of the electromagnet thereby produced, the free end of said reed being disposed adjacent the free end of said reverse portion and a pole piece thereon of magnetically permeable material whereby said reed is controllable by 55 said electromagnet.

2. An article of manufacture consisting of a mechanical interrupter unit for a potential changer adapted for use with a direct current source as the "B" supply of a radio receiver, 60 said unit comprising a base formed of a single piece of magnetic permeable material having an elongate shank, a transverse portion integral with one end of said shank and a reverse portion integral with the outer end of said transverse 65 portion and having its free end extending toward the other end of said shank, a magnetic coil mounted on said reverse portion, a vibratory reed of magnetic permeable material mounted on said other end of the shank, said vibratory 70 reed having the major portion of its body disposed substantially parallel to the axis of said reverse portion with its free end extending toward the free end of said reverse portion to constitute one pole of said magnetic coil.

3. As an article of manufacture, a mechanical interrupter comprising an elongated base formed of a single piece of magnetically permeable material bent into a rectangular hook shape so as to comprise an elongated shank, a transverse portion integral with and substantially perpendicular to one end of said shank and a reverse portion integral with the outer end of said transverse portion and extending toward the other end 10 of said shank with its axis disposed substantially parallel to said shank, a magnetic coil mounted on said reverse portion whereby said portion comprises the core for said coil, an elongated vibratory reed mounted on the last-mentioned end of said shank with the major portion 15 of the body thereof disposed substantially parallel to the axis of said core and the free end thereof disposed adjacent to and offset from the free end of said core.
- 20 4. As an article of manufacture, a mechanical interrupter comprising an elongated base formed of a single piece of magnetically permeable material bent into a rectangular hook shape so as to comprise an elongated shank, a transverse portion integral with and substantially perpendicular to one end of said shank and a reverse portion integral with the outer end of said transverse portion and extending toward the other end of said shank with its axis disposed 25 substantially parallel to said shank, a magnetic coil mounted on said reverse portion whereby said portion comprises the core for said coil, an elongated vibratory reed of magnetically permeable material mounted on the last-mentioned end of said shank with the major portion of the 30 body of said reed disposed substantially parallel

to the axis of said core and the free end thereof disposed adjacent to and offset from the free end of said core for movement substantially transversely of the axis of said core whereby the free end of said reed constitutes one pole of 5 said magnetic coil.

5. A vibratory motor comprising, in combination, a frame formed of a continuous piece of material bent into a rectangular hook shape and comprising an elongated shank, a transverse portion integral with one end thereof and substantially perpendicular thereto and a reverse portion integral with the outer end of said transverse portion and extending toward the other end of said shank with its axis substantially 10 parallel thereto, a magnetic coil mounted on said reverse portion and a vibratory reed secured to said other end of the shank and extending toward the free end of said reverse portion.

6. A vibratory motor comprising, in combination, a frame formed of a continuous piece of magnetic permeable material bent into a rectangular hook shape and comprising an elongated flat shank, a transverse portion integral with one end thereof and substantially perpendicular thereto and a reverse portion integral with the outer end of said transverse portion and extending toward the other end of said shank with its axis substantially parallel thereto, a magnetic coil mounted on said reverse portion whereby 25 said portion comprises the core for said coil and said coil and core form an electromagnet, and a vibratory reed secured to said other end of the shank and extending to a position for co-operation with said electromagnet.

20 25 30 35
